UNITED STATES PATENT OFFICE.

JOHN T. HAMPTON AND ROBERT E. L. EAGLE, OF ENGLEND, ARKANSAS.

SHADE-ROLLER BRACKET

No. 889,826.

Specification of Letters Patent. © Patented June 9, 1908.

Application filed December 24, 1907. Serial No. 407,959.

To all whom it may concern:

Be it known that we, JOHN T. HAMPTON and ROBERT E. L. EAGLE, citizens of the United States, residing at England, in the county of Lonoke and State of Arkansas, have invented a new and useful Shade-Roller Bracket, of which the following is a specification.

This invention relates to a shade roller support, and has for one of its objects to provide a simple, cheap and strong bracket for each end of a shade roller that requires no skill to put in place on a window frame, but may be applied or removed with the greatest ease and with few or no tools. To this end the bracket, which is preferably flat with a round neck and extended bearing collar, has a screw stem projecting from said neck, by means of which stem the bracket is screwed into a window frame until the collar bears against the same, relieving the screw stem from downward strain which would tend to bend it, and establishing the proper distance from the window frame of the shade roller.

Another object of the invention relates to a simple means for adjusting the bracket to relatively increase and decrease the length thereof whereby the same brackets may be employed to hang shades of any length and with any diameter of roller.

A further object of the invention is directed to the means for fastening the screw stem to the bracket, the construction being such that should the screw bend or break, it could be removed from the bracket and a new one substituted without trouble.

With these and other objects in view the invention consists of the novel combination and arrangement of parts hereinafter described and claimed, reference being had to the accompanying drawing, in which,

Figure 1 is an elevation of a portion of a window showing a shade and its roller supported in the improved brackets; Fig. 2 is a perspective view of the bracket for supporting the flat pintle of the roller; Fig. 3 is a similar view of the bracket in which the round pintle turns but seen from the opposite end; Fig. 4 is an elevation of one of the brackets partly in section showing the preferred form of fastening the screw stem in place; Figs. 5 and 6 are views of modified forms of the bracket, and Fig. 7 is a detail view showing a bracket attached to a window frame in a position different from that shown in Fig. 1.

Similar numerals of reference are used for the same parts on all the figures.

The shade roller here shown is the well-known type of spring roller having a round pintle 2 at one end and a flat pintle 3 attached to the retracting spring at the other end. These pintles rest in and are supported by brackets 4 and 5 respectively, fastened to the top of a window frame.

Each bracket comprises a screw stem 6, to enter the window frame, that projects from a neck 7 on which is adjustably threaded a polygonal collar or nut 8, the inner face of which bears against the window frame when the stem 6 is screwed home and holds the bracket in true position. As the face of the collar or nut 8 is relatively large, the liability of bending the screw stem when the collar is against the window frame is very remote. At the opposite end of the neck 7 is a flat elliptical, circular, or other shaped plate 9 lying in a plane coincident with the axis of the screw stem 6 and neck 7 and, when in place on the window frame, vertically disposed. The plate 9 of the bracket 4 has a circular perforation 10 for the round pintle 2 of the shade roller, whereas the similar plate 9 of the bracket 5 is provided with a vertical slot 11 enlarged at the bottom as usual to receive and retain the flat pintle 3 on the opposite end of the shade roller. The mouth of the slot 11 at the upper edge of the plate is widened to enable the pintle 3 to be more easily placed therein.

The neck 7 of each bracket as heretofore stated, carries a threaded collar or nut 8 which may be screwed up or down on the neck to change the distance between the pintle opening in the plate 9 and the flat bearing face on said collar, or the window frame. Constructed in this manner brackets of but one size need be made, as they can be adjusted easily and quickly to suit rollers of large or small diameters.

The bracket is preferably made of malleable or stamped metal with the screw stem attached in the manner clearly shown in Fig. 4. As there disclosed, the neck 7 has a transverse slot 12 extending inwardly from the end into which the flattened end 13 of the screw stem 6 fits and is clamped firmly therein by screwing the collar or nut 8 on the neck 7.

Instead of flattening the head end of the screw stem 6 its entire length, the slotted

portion of the neck 7 may be bored out a portion of its length as shown in Fig. 5 and a screw with a short flattened portion inserted therein and clamped firmly by the collar or nut 8, or, the neck may be threadless and slightly tapered, as in Fig. 6 and the collar driven thereon instead of being screwed on.

When window frames are deep, owing to thick walls, it is sometimes desirable to place 10 the shades near the sash. In this case the brackets will be screwed into the under side of the window frame, as represented in Fig. 5, instead of in the face of the frame.

What is claimed is:

- 15 1. A shade roller bracket comprising a flat plate having a slotted neck and an opening for the roller pintle, a screw stem fitted in said slotted neck, and a collar movable on said neck for holding the screw stem fixed.
- 20 2. A shade roller bracket comprising a flat plate having an opening for the roller pintle and a neck slotted at its end, a screw stem having an end fitted in said slot, and a collar adapted to be screwed on said neck to

fasten the screw stem in said slot and to 25 change the effective length of said neck.

3. A shade roller bracket comprising a flat elliptical plate having an opening for the pintle of a shade roller and a threaded neck 30 projecting from the edge thereof, said neck having a slot made in its end, a screw stem formed with a flat head end to enter said slot, and a collar having a flat face perpendicular to the axis of the stem screwed on said neck to hold said stem fixed and to change the 35 distance between said pintle opening and the plane of the flat face of the collar or nut, said flat face adapted to bear against the face of a window frame.

In testimony that we claim the foregoing, 40 as our own, we have hereto affixed our signatures in the presence of two witnesses.

JOHN T. HAMPTON.
ROBERT E. L. EAGLE.
